UNITED STATES PATENT OFFICE.

EDWARD A. HENKLE, OF PHILADELPHIA, PENNSYLVANIA.

CUTTING APPARATUS FOR SHEETS CONTAINING PRINTED MATTER.

SPECIFICATION forming part of Letters Patent No. 634,342, dated October 3, 1899.

Application filed April 24, 1899. Serial No. 714,283. (No model.)

To all whom it may concern:

Be it known that I, EDWARD A. HENKLE, a citizen of the United States, residing at Philadelphia, in the county of Philadelphia and State of Pennsylvania, have invented new and useful Improvements in Methods of and Apparatus for Cutting Sheets Containing Printed Matter, of which the following is a specification.

10 In certain classes of printing it is common to set up the matter to be printed a number of times in separate forms and to print from the different forms at the same operation of the press, afterward cutting up the sheets on which the different impressions are made into sections or strips, each section or strip containing a single impression. This is not only very convenient, but extremely economical when a large number of printed articles are 15 to be produced. It is particularly useful in printing cards, tickets, and the like which are small in size in that it reduces the press-work necessary to their production to a minimum. Considerable difficulty, however, has 20 been met with in cutting the sheets containing the different impressions to the exact size desired and in so locating the cuts that the different sections will have the impressions thereon properly located. Especially is this 25 the case when the sheets are printed on rotary presses and the sheets are in the form of long narrow strips. This difficulty is due to the tendency of the sheets when placed in piles to "crawl," thereby making some of the 30 piles wider or narrower than others, or to a tendency of one part of the pile to crawl more than another when the pile is subjected to frequent clampings and bodily movements, making the pile wider or narrower at the top 35 than at the bottom. This crawling action will almost invariably take place when a large number of cuts are to be made, especially if the material on which the printing is done be cardboard, the glazed surface of which permits the slipping of the sheets one upon the 40 other.

My invention is designed to overcome the difficulties and inconveniences above noted; and it consists of the novel features of construction and combinations of parts, which 45 will be hereinafter more fully described and claimed.

In the drawings forming part of this specification, Figure 1 is a perspective view of two coöperating printing-cylinders, showing the 55 punching mechanism thereon. Fig. 2 is a plan view of the bed of the cutter with my improvements applied. Fig. 3 is a face view of one of the printed sheets or strips. Fig. 4 is a detail perspective view of the cutter-bed. 60 Fig. 5 is a similar view of the slide, and Fig. 6 is a perspective view showing a pile of sheets or strips on the slide in position to be cut.

Like reference-numerals indicate like parts 65 in the different views.

In carrying out my invention I provide at a convenient point in the form-cylinder 1 a punch 2, which registers with a die 3 in the impression-cylinder 4, so that as the sheets 70 or strips are fed between said cylinders for the purpose of printing said punch will cut or nip out a hole 5, which hole will of course occupy on each sheet exactly the same relative position with respect to the printed matter on the sheet. In addition to the punching mechanism on the printing cylinders 1 and 4 I provide certain improvements in the cutter, as clearly illustrated in the drawings. The bed 6 of the cutter is provided with parallel longitudinally-extending guide-flanges 77 on its upper side, between which is located and adapted to move a slide or supplemental bed 8, the same being provided with an upwardly-extending register-pin 9 at one 80 end thereof. Said slide is further provided at regular intervals throughout its length with transversely-extending parallel cutting-sticks 10, which are inlaid in the slide and lie flush with the upper surface thereof. 85 Against these sticks the cutting-blade 11 is adapted to act, the same serving to prevent dulling the edge thereof. Along one side of the slide 8 and extending upwardly therefrom are guide-pins 12, the same being arranged 90 in line with each other and preferably at equal distances from the side edge of the slide. The said slide is further provided on the edge opposite that along which the guide-pins are arranged with a series of ratchet-teeth 13, which are adapted to be engaged by a pawl 14. The said pawl is pivotally mounted upon a bracket 15, adjustably secured to the bed 6 by means of a screw 16, which ex-

tends through an elongated slot 17 in said bracket. Said bracket is adapted to be moved when said screw is loosened by means of a milled nut 18, which engages a threaded shank 19 on said bracket. The pawl 14 is normally held in position to engage the teeth 13 by means of a spring 20, which is secured to said pawl and to the bracket 15. A handle 21 is provided on the slide 8, by means of which the same may be operated, and a stop 22 is secured to the bed, against which the pawl 14 is adapted to bear.

After the hole 5 has been punched in the sheets containing the different impressions 15 said sheets are piled upon the slide 8, with the register-pin 9 thereon extending through the holes 5 therein and with the side edges of said sheets in contact with the guide-pins 12 12, the same being held in this position by 20 means of a clamp of any suitable form or construction. It being now desired to cut the sheets in the pile into sections, the cutting-blade 11 is actuated and the sheets are severed along the line of the first cutting-stick 10 on the slide 8. The said slide is then moved outwardly by means of the handle 21 until the pawl 14 passes from one of the teeth 13 to the next one or slightly beyond it. The said slide is then moved inwardly, so as to 25 bring the engaging end of the pawl 14 in contact with the shouldered portion of the tooth 13 with which it has been brought into engagement. When in this position, the actuation of the cutting-blade 11 will sever the sheets in the pile along the line of the second cutting-stick 10, it being of course understood that the teeth 13 are so arranged on the slide 8 that the distance between them is exactly equal to the width or length of the sections into which the sheets are to be divided. 30 During the outward movement of the slide 8 it will of course be understood that the pawl 14 will ride over the inclined walls of the teeth 13 in succession and in doing so be 35 swung upon its pivotal connection with the bracket 15. When, however, the outermost point of a tooth has been passed, said pawl will be returned to its normal position by means of the spring 20. If it be desired at 40 any time to adjust the pawl 14 so as to change the point of severance of the sheets by the cutting-blade 11, the same may be readily done by loosening the screw 16 and moving the bracket 15 by the nut 18, as heretofore 45 described. When the proper adjustment of the pawl has been made, the same is locked in adjusted position by the screw 16.

It will be understood, of course, that the illustration herein and the foregoing description relate to but one embodiment of my invention.

Various changes in the details of construction may be made without departing from the nature or spirit of the invention, and I do not care to be limited to the exact construction shown and described, except as defined by the following claims. For example, other

means might be adopted in lieu of the ratchet-teeth 13 and the pawl 14 for enabling the slide 8 to be fed alternately a certain predetermined distance. I therefore reserve to myself the right to adopt such other means as may be found convenient or expedient.

Having now described my invention, what I claim as new, and desire to secure by Letters Patent, is—

1. In cutting mechanism for sheets having slots or perforations therein, occupying the same relative positions in each sheet, the combination with the bed and the cutting-blade, of a slide on said bed on which a pile of said sheets is placed, a register-pin on said slide extending through the openings in said sheets, and guides for the edges of said sheets, as and for the purpose set forth. 80

2. In cutting mechanism for sheets having slots or perforations therein, occupying the same relative positions in each sheet, the combination with the bed and the cutting-blade, of a slide on said bed on which a pile of said sheets is placed, a register-pin on said slide extending through the openings in said sheets, and a series of guide-pins arranged in line with each other along one side of said slide and against which the edges of said sheet are 90 adapted to bear, as and for the purpose set forth. 95

3. In cutting mechanism for sheets having slots or perforations therein, occupying the same relative positions in each sheet, the combination with the bed and the cutting-blade, of a slide on said bed on which a pile of said sheets is placed, a register-pin on said slide extending through the openings in said sheets, guides for the said edges of said sheets, and 100 means for limiting the successive movements of said slide in one direction, to enable the same to be fed equal distances, as and for the purpose set forth. 105

4. In cutting mechanism for sheets having slots or perforations therein, occupying the same relative positions in each sheet, the combination with the bed and the cutting-blade, of a slide on said bed on which a pile of said sheets is placed, a register-pin on said slide 110 extending through the openings in said sheets, guides for the side edges of said sheets, and 115 automatic stopping mechanism for the slide, whereby step-by-step movements of predetermined length may be imparted to said slide, 120 as and for the purpose set forth.

5. In cutting mechanism for sheets having slots or perforations therein, occupying the same relative positions in each sheet, the combination with the bed and the cutting-blade, of a slide on said bed on which a pile of said sheets is placed, a register-pin on said slide 125 extending through the openings in said sheets, guides for the side edges of said sheets, automatic stopping mechanism for the slide, 130 whereby step-by-step movements of predetermined length may be imparted to said slide, and means for adjusting said stopping mechanism, as and for the purpose set forth.

6. In cutting mechanism for sheets having slots or perforations therein occupying the same relative positions in each sheet, the combination with the bed and the cutting-blade, of a slide on which a pile of said sheets is placed, a register-pin on said slide extending through the openings in said sheets, guides for the side edges of said sheets, ratchet-teeth on said slide, and a spring-actuated pawl on the bed adapted to engage said teeth, as and for the purpose set forth.

7. In cutting mechanism for sheets having slots or perforations therein, occupying the same relative positions in each sheet, the combination with the bed and the cutting-blade, of a slide on which a pile of said sheets is placed, a register-pin on said slide extending through the openings in said sheets, guides for the side edges of said sheets, ratchet-teeth on said slide, a spring-actuated pawl on the bed adapted to engage said teeth, and means for adjusting the position of said pawl, as and for the purpose set forth.

8. In cutting mechanism for sheets having

slots or perforations therein, occupying the same relative positions in each sheet, the combination with the bed and the cutting-blade, of a slide on said bed on which a pile of said sheets is placed, a register-pin on said slide extending through the openings in said sheets, guides for the side edges of said sheets, ratchet-teeth on said slide, a spring-actuated pawl engaging said teeth, a bracket having an elongated slot therein on which said pawl is pivotally mounted, a set-screw extending through said slot by means of which said bracket is adjustably secured to said bed, and means for moving said bracket in one direction or the other, as and for the purpose set forth.

In testimony whereof I have hereunto set my hand in presence of two subscribing witnesses.

EDWARD A. HENKLE.
